Charles H. Wesson
ATTORNEY

UNITED STATES PATENT OFFICE.

LEON S. BRACH, OF EAST ORANGE, NEW JERSEY.

LIGHTNING-ARRESTER CONSTRUCTION.

Application filed May 17, 1919. Serial No. 297,746.

To all whom it may concern:

Be it known that I, LEON S. BRACH, residing at East Orange, county of Essex, and State of New Jersey, have invented certain new and useful Improvements in a Lightning-Arrester Construction, of which the following is a specification.

This invention relates to protective devices designed for the protection of low voltage apparatus and devices from injury due to abnormal electric discharges through the line, such for instance as lightning discharges or such discharges as might occur when a telephone, telegraph, or signal wire becomes crossed with a line of high potential. The present invention deals more particularly with lightning arresters of the vacuum type where spaced electrodes are enclosed in an evacuated container or in a closed vessel containing a rarefied inert gas.

One of the objects of the invention is to provide an arrester of the class described, which will be strong, durable and practically immune from external shocks and jars, sudden external changes in temperature as well as sudden internal changes in temperature produced by abnormal discharges through the arrester.

The invention of the present arrester, while in its broad aspect is similar to that disclosed in my co-pending application Serial Number 297,747, has the additional advantage providing for the care of an additional circuit without enlarging or complicating the internal construction of the arrester.

Other features of the invention reside in the construction of the head mountings of the arrester and the manner of mounting the terminal members therein.

Other objects and aims of the invention, more or less specific than those referred to above, will be in part obvious and in part pointed out in the course of the following description of the elements, combinations, arrangements of parts and applications of principles, constituting the invention, and the scope of protection contemplated will be indicated in the appended claims.

In the accompanying drawing, wherein I have illustrated a preferred form of embodiment of my invention:

Figure 1 is a longitudinal sectional view taken through the arrester.

Figure 2 is an elevational view of the exterior of the arrester.

Figure 3 is a horizontal sectional view taken on the line 3—3 of Figure 1; and

Figure 4 is a top plan view of the arrester.

Referring now to the drawings, wherein similar reference characters refer to similar parts throughout the several views thereof, the reference numeral 1 denotes the evacuated glass container, to the ends of which are sealed the leading-in wires 2 and 3.

The leading-in wire 2 passes through a block 4 formed of a high heat resisting insulating material, such as porcelain, or the like.

Seated in a circular recess 5 formed in the block 4, is an electrode 6. The leading-in wire is suitably electrically connected with this electrode. In the present instance it extends through an aperture drilled therethrough, and suitably fastened therein, for instance, as by means of solder.

Although various metals may be employed in forming the electrode, I preferably employ nickel steel in this relation, owing to the fact that this material has the advantage of not emitting gas or the heat generated by a discharge through the arrester.

Surrounding the electrode 6, and suitably spaced therefrom to provide a spark gap of the desired dimensions, is a tubular electrode 7, likewise preferably formed of nickel steel. This electrode at one end encircles the block 4 and engages with a shoulder 8 formed upon the rear portion of the block 4.

9 indicates a block of insulating material similar to block 4, through which extends the leading-in wire 3, an electrode 10 also preferably formed of nickel steel being seated in a recess 11, provided in the block 9, the leading-in wire 3 extending through an aperture drilled in the electrode and being electrically connected to said electrode.

It will be noted that the electrodes 6 and

- 10 are spaced apart a sufficient distance so that no arcing will take place therebetween, the spark gaps being formed between the block electrodes and the tubular electrode 7.
- 5 The electrode 7 is not a complete cylinder, but is preferably formed of a sheet of metal bent into the form of a cylinder with the free ends of the sheet spaced slightly apart from end to end, leaving a recess or 10 slot from end to end of the device, as indicated at 12.
- The primary purpose of this slot is to permit of the viewing of the interior of the device, so that the condition of the 15 spaced electrodes located in the vacuum chamber may at all times be observed. This construction of the electrode, however, has a further advantage in that when assembling it with the insulating blocks 4 and 9 a more 20 perfect fit between the parts is assured inasmuch as the cylinder will be strong enough to accommodate slight imperfections or irregularities which often appear in porcelain parts.
- 25 Surrounding the electrode 7 is a cylindrically formed sheet of mica 13, the same being located between the circular electrode 7 and the inside surface of the glass container.
- The glass container 1 is preferably 30 enclosed in a cylinder 14 formed of a tough, heat resisting, insulating material, such as fibre, although other materials, such as a composition containing asbestos may be advantageously used in this relation. This 35 cylinder quite closely embraces the glass container and is provided with an elongated slot or opening 15, which when the device is assembled, is located directly opposite the slot or opening 12 in the electrode 7. The 40 interior of the arrester it will be noted, can be viewed through these registering openings, the mica shield and the transparent wall of the glass container.
- Fitted upon the lower end of the fibre 45 tube 14 is a metallic cap 16, having a circular opening, the edges of which are adapted to be received in a slot or recess 17 formed in the terminal member 18, the latter having a central bore through which 50 extends the leading-in wire 3. The terminal member 18 in its outer end is provided with a recess 19 adapted to receive a body of solder 20, which mechanically and electrically connects the leading-in wire 3 to the terminal. The suitable nuts and washers 55 21 are threaded upon the terminal member 18, adapting it to be attached to a line or with ground.
- 60 Located in the opposite end of the tubular member 14 is a block 22 which is preferably formed of a moldable insulating material, such for instance as porcelain or bakelite, the construction being such that the terminal member 23 may be molded therein, a suitable recess 24 in the terminal member 65 insuring against its displacement from the moldable material composing the block 22.
- Mounted upon the upper end of the cylinder 4 is a metallic cap 25, which may be attached thereto as by means of pins 26, 70 which pass through the wall of the cylinder 14 into the block 22, this construction holding the cylinder 14, the head 22 and the metallic cap in fixed relation.
- Seated in a recess 27 formed in the tubular electrode 7 and extending upwardly therefrom, and sealed through the wall of the glass container, is a second leading-in wire 28, the same passing through an aperture 29 formed in the upper end of the cylinder 14 and being received in a recess 30 provided in the metallic cap 25 and soldered or brazed to the wall of this recess so as to make a mechanical and electrical connection therewith. The leading-in wire 2 extends through a bore or aperture provided in the terminal member 23, and is fastened thereto as by means of a body of solder 31, located in a recess 32 formed in the upper end of the stem or post 33 of the terminal 90 member 23. The stem or post 33 of the terminal member 23 may be threaded to receive clamp nuts so that it may be attached to the line wire, or permitting it to be attached to a supporting base, such as illustrated in my co-pending application Serial Number 297,745.
- It will accordingly be seen that I have provided a construction well adapted to attain, among others, all the ends and objects 100 above pointed out in an exceedingly simple yet efficient manner. The structure is strong, durable, rigid, and while possessing the advantage of having an evacuated glass container has, as well, the other advantages 105 inherent in metallic arresters. Moreover, the construction is such that the interior of the device can at all times be viewed and the condition of the spaced electrodes located in the vacuum chamber thereby ascertained.
- 110 It will be obvious that the terminals 18 and 33 may be each connected with a different line wire and the metallic cap 30 connected with the electrode 7 with ground, or that said cap and one of the terminals may be each connected with a line wire, and the other terminal with ground; the device as indicated operating to connect two lines with ground.
- 115 It will be further noted that the construction is such that no strain is placed upon the evacuated glass container, the same being internally and externally protected by the fibre cylinder 14 externally and internally by the mica shield 13. This insures against breaking of the container and the destruction of the vacuum.
- 120 As many changes could be made in this

construction without departing from the scope of the following claims, it is intended that all matter contained in the above description or shown in the accompanying drawing shall be interpreted as illustrative only and not in a limiting sense.

Having thus described my invention what I claim as new and desire to secure by Letters Patent is:

- 10 1. In a device of the class described, the combination with an evacuated container of a plurality of electrodes mounted therein, leading-in wires extending through the walls of said container and connected with said electrodes, an insulating casing surrounding said container and provided with a head of insulating material located in one end thereof, a terminal member mounted in said head, one of the leading-in wires extending 20 through said head and connected with said terminal member, a metallic member mounted on the end of the casing adjacent the head, one of the leading-in wires being connected with said member, and a metallic cap provided with a terminal member positioned upon the other end of said container, another of said leading-in wires being connected with said terminal member.

- 25 2. In a device of the class described, the combination with an evacuated container, leading-in wires sealed through the walls of said container and connected at their inner ends to electrodes, a tubular electrode surrounding said first named electrodes and spaced therefrom, a casing of insulating material surrounding said evacuated container, a head formed of insulating material mounted in one end of said casing, and a pair of terminal members on said head to 40 which leading-in wires are connected.

- 30 3. In a device of the class described, the combination with an evacuated container, of leading-in wires sealed through the walls of said container, an electrode carried by the inner end of each of said leading-in wires, a tubular electrode surrounding said first named electrodes and spaced therefrom, a casing of insulating material surrounding said evacuated container, a head formed of 45 insulating material mounted in one end of said casing, a metallic cap mounted upon the end of the casing adjacent the head, a wire leading from said cap through the walls of said evacuated container, and connected with said tubular electrode, and a terminal member carried by said head to which one of said leading-in wires is attached.

- 40 4. In a device of the class described, the combination with an evacuated container, of leading-in wires sealed through the walls of said container, and electrode carried by the inner end of each of said leading-in wires, a tubular electrode surrounding said first-named electrodes and spaced there-

from, an insulating casing surrounding said 65 evacuated container, a head of insulating material surrounding said evacuated container, a head formed of insulating material mounted in one end of said casing, a metallic cap mounted on the end of said casing 70 adjacent said head, a wire connected with said cap and said tubular electrode passing through the walls of said evacuated container, a terminal member mounted in said head to which one of said leading-in wires 75 is attached, and a metallic cap carried upon the other end of said casing provided with a terminal member to which another of said leading-in wires is attached.

5. In a device of the class described, the 80 combination with an evacuated container, of a plurality of electrodes mounted therein, and provided with leading-in wires extending through the wall of said container and connected with said electrodes, an insulating 85 casing surrounding said container, a single head of insulating material located in one end of said casing, terminal members mounted in said head and connected to leading-in wires, one of said wires extending 90 through said head.

6. In a device of the class described, the combination with an evacuated container, of a plurality of electrodes mounted therein and connected to leading-in wires extending 95 through the wall of said container, a casing of insulating material surrounding said container, a head of insulating material located on one end of said casing, a terminal member mounted in said head and connected to one of said electrodes by a leading-in wire extending through said head, and a metallic member mounted upon the end of said casing adjacent the head, said metallic member being connected to another 100 105 of said leading-in wires.

7. In a device of the class described, the combination with an evacuated container, a pair of block electrodes located therein, insulating supports for said blocks, leading-in wires extending through the walls of said evacuated chamber connected with said electrodes, a tubular electrode carried by the supports of said first-named electrodes and surrounding the latter, a leading-in wire 110 115 extending through the walls of said evacuated container and connected with said tubular electrode, a casing formed of insulating material surrounding said container, a block of insulating material located in one end of said casing, a terminal member molded into said head, one of said leading-in wires extending through said head and through a bore provided in said terminal member so as to be mechanically and electrically connected therewith, a metallic cap mounted upon the last described end of said casing, means for uniting said cap and said casing 120 125

to said head, the leading-in wire of said tubular arrester being connected with said cap, a metallic cap positioned upon the opposite end of said casing, a terminal member carried thereby, the leading-in wire of one of said first named electrodes extending through said cap and having electrical and

mechanical connection with said terminal member.

8. A lightning arrester having a vacuous 10 container and an open-ended tubular envelop about the electrodes.

In testimony whereof I affix my signature.

LEON S. BRACH.
